By T. Play Linday

his Attorney

UNITED STATES PATENT OFFICE.

JOHN H. DOWD, OF HARTFORD, CONNECTICUT, ASSIGNOR TO THE BILLINGS & SPENCER COMPANY, OF HARTFORD, CONNECTICUT, A CORPORATION OF CONNECTICUT.

ADJUSTABLE SOCKET WRENCH.

Application filed May 3, 1926. Serial No. 106,212.

This invention relates to socket wrenches of the type having a brace and a socket head provided with a plurality of angularly spaced sockets varying in size from one another, the socket head being rotatable to bring the desired socket into operative position, and the head being locked in any one of its predetermined adjusted positions.

The object of the present invention is to provide a wrench of this sort having various features of novelty and advantage and which is particularly characterized by its simplicity and economy in manufacture, its strength and durability, and the ease and facility with which the socket head may be adjusted and locked in place.

Other objects will be in part obvious and in part pointed out more in detail hereinafter.

20 The invention accordingly consists in the features of construction, combination of elements and arrangement of parts which will be exemplified in the construction herein-after set forth, and the scope of the application of which will be indicated in the appended claims.

In the accompanying drawings, wherein I have shown one embodiment which the present invention may take;

30 Figure 1 is an elevational view of my improved wrench; and

Fig. 2 is a sectional view taken substantially on line 2—2 of Fig. 1.

Referring to the drawings in detail, 10 designates generally a brace of any suitable construction and having at one end a handle 11 and at the other end a yoke or fork provided with parallel arms 12 between which the socket head is mounted.

40 The socket head, which may be of any suitable construction, is here shown as being a forged member having a hub 15, and a plurality of radiating arms 16, each arm having, in its outer end, a nut socket 17. The sockets vary in size from one another so as to accommodate nuts of different sizes. The socket head is fixed, as by means of a pin 18, to a gudgeon member 19. This gudgeon member, which may be in the form of a 45 polygonal, for instance square, rod, extends axially through the hub 15, and its squared ends engage in alined openings adjacent the free ends of the arms 12 of the yoke. These openings, at their outer ends, as at 20, are 50 of sufficient diameter or size to allow the

member 19 to turn therein, and the other portions 21 of the openings have straight parallel sides so as to closely receive the ends of the gudgeon member 19 and hold it and the socket head against turning when 60 the wrench is in operative condition. For the purpose of maintaining the head, when the wrench is in use, with the gudgeon member 19 engaging in the squared portions 21 of the openings, there is provided a friction 65 washer 25 which is urged against the inside face of one of the arms 12 by a spring 26 mounted in a counterbore 27 at one end of the hub portion 15. The washer 25 is preferably provided with an annular rib or boss 70 28 which slides in the outer end of the counterbore 27 so that the washer is properly maintained in position.

It will be seen, from the foregoing description taken in connection with the accompanying drawings, that when it is desired to adjust the socket head so as to bring a socket of desired size into operative position, the socket head, as a whole, is moved or slid outwardly so as to bring the gudgeon 75 member 19 from the position shown in Fig. 1 to a position where the gudgeon member engages in the circular portions 20 of the slots. Then the socket head is turned to the desired position and moved inwardly to 80 towards the brace so as to again engage the squared ends of the gudgeon member 19 in the squared portions 21 of the slots. The friction washer and spring maintain the socket head in its locked position, that is to 85 say, with the gudgeon member 19 engaging in the squared portions 21 of the slots.

It will be noted that my improved structure is very simple in construction, comprising but relatively few parts, each of which 90 may be economically manufactured. The adjustment of the socket head may be had with facility, it being unnecessary to operate any separate locking members, such as plungers or the like. When the head has 95 been properly adjusted, it is maintained in locked relation to the brace in a very effective and simple manner. The tool is very strong and is enabled to withstand very severe usage.

As many changes could be made in the above construction and many apparently widely different embodiments of this invention could be made without departing from the scope thereof, it is intended that all mat- 100 105 110

ter contained in the above description or shown in the accompanying drawing shall be interpreted as illustrative and not in a limiting sense.

5 It is also to be understood that the language used in the following claims is intended to cover all of the generic and specific features of the invention herein described and all statements of the scope of the invention which, as a matter of language, might be said to fall therebetween.

I claim as my invention:

1. A wrench of the character described having an adjustable socket head provided 15 with a plurality of angularly spaced apart sockets of different sizes, and polygonal gudgeons; a brace having a pair of spaced arms between which said head is positioned, said arms having alined slots provided with 20 portions in which said gudgeons are adapted to turn when adjusting the head, said slots having other portions closely receiving said gudgeons for locking the head against rotation when the parts are in operative relation, and means for frictionally holding said 25 head in a position where said gudgeons engage in the last mentioned portions of said slots.

2. A wrench of the character described 30 having a brace provided with a pair of spaced arms, said arms having alined slots, each slot having a square portion and an enlarged portion, an adjustable socket head slidably mounted between said arms, a 35 gudgeon member passing axially through said socket head to which it is fixed and having square ends adapted to turn in the enlarged portions of said slots and non-rotatable in the square portions of said slots, 40 and frictional means for holding said head

with the gudgeon member engaging in the square portions of the slots.

3. A wrench of the character described 45 having an adjustable socket head provided with a plurality of angularly spaced apart sockets of different sizes, and polygonal gudgeons; a brace having a pair of spaced arms between which said head is positioned, said arms having alined slots provided with 50 portions in which said gudgeons are adapted to turn when adjusting the wrench, said slots having other portions closely receiving said polygonal gudgeons for locking the head against rotation when the parts are in operative 55 position, a washer carried by said head and engaging one of said arms, and a spring urging said washer against said arm.

4. A wrench of the character described 60 having an adjustable socket head provided with a hub portion and a plurality of radially extending arms, each with a socket in its outer end, a gudgeon member passing through and fixed to said hub and having square ends, one end of said hub portion being counterbored, a brace having a pair of 65 spaced arms between which said socket head is positioned, said arms having alined slots provided with portions in which said gudgeon member is adapted to turn when adjusting the wrench, said slots having square 70 portions closely receiving the square ends of said gudgeon member for locking the head against rotation when the parts are in operative relation, a washer on one end of said hub and having a boss engaging in said counterbore, and a spring in said counterbore normally urging said washer against one of said arms.

JOHN H. DOWD.
